 Allen-Bradley Company, Milwaukee, Wis., a
 Corporation of Wisconsin

Application November 12, 1931
 Serial No. 574,517

6 Claims. (Cl. 200—83)

This invention relates to electric switches and refers more particularly to the actuating mechanism of switches controlled from relatively slow moving elements such as pressure switches, float switches, and the like.

It is an object of this invention to provide a novel mechanism for translating a relatively slow motion into a quick positive snap action suitable for opening and closing electric switches and for actuating similar appliances.

Another object of this invention is to simplify the design and construction of devices of this nature so as to facilitate manufacture and reduce the cost thereof.

Another object of this invention is to provide a compact unitary construction in which the entire mechanism is mounted from a single comparatively small tubular supporting member, so as to effect a substantial reduction in overall size and greatly increase its applicability to varying installation requirements.

And a further object of this invention is to employ a spring enclosure for the supporting base of the entire mechanism.

With the above and other objects in view which will appear as the description proceeds, this invention resides in the novel construction, combination and arrangement of parts substantially as hereinafter described and more particularly defined by the appended claims, it being understood that such changes in the precise embodiment of the herein-disclosed invention may be made as come within the scope of the claims.

In the accompanying drawings, one complete example of the physical embodiment of this invention is illustrated constructed according to the best mode so far devised for the practical application of the principles thereof, and in which:

Figure 1 is a cross section taken through a pressure switch embodying this invention;

Figure 2 is a front plan view of the switch with the cover of its enclosing casing broken away and the spring and its associated retaining stops removed;

Figure 3 is a side view of the structure with portions broken away and in section and illustrating the parts in the positions they occupy with the switch open;

Figure 4 is a perspective view of the diaphragm follower, the spring and associated elements, separated, but arranged in their proper order of assembly; and

Figure 5 is a fragmentary bottom view taken on the plane of the line 5—5 of Figure 2.

Referring now more particularly to the accompanying drawings, the numeral 5 represents a cylindrical housing which, as will be later described, forms the support of the entire mechanism. This cylindrical housing has a flange 6 at one end and is internally threaded as at 7 at its other end.

Closing the end of the cylindrical housing adjacent the flange 6 is a diaphragm 8 of rubber or other suitably flexible material. The peripheral edge portion of the diaphragm 8 overlies the flange 6 and is securely clamped between the flange 6 and a diaphragm cover 9. The cover 9 is in the form of a shallow cup whose diameter is substantially equal to that of the cylindrical housing and has an annular flange 10 similar to the flange 6.

A plurality of circumferentially arranged bolts 11 passing through aligned openings in the flanges 6 and 10 and the diaphragm, serve to connect the flanges and clamp the diaphragm peripheral edge portion therebetween.

The diaphragm cover, with the diaphragm thus forms a chamber which may be communicated with a source of pressure, not shown, through a pipe line 12 or other means of communication threaded in a nipple 13 fixed to the diaphragm cover. The relatively slow movement of the diaphragm 8 effected by pressure changes within this chamber, is translated into a quick positive snap action to open and close the switch indicated generally by the numeral 14, in a manner now about to be described.

Slightly inwardly of the flanged end of the cylindrical casing 5 is a fixed guide plate 15. The plate extends across the cylindrical housing and has a central opening 16 surrounded by four equi-spaced openings 17 near its outer edge. Positioned between the guide plate 15 and the diaphragm is a plate 18 which lies flat against the diaphragm. This plate 18 has a central stud 19 fixed thereto to project through the opening 16 in the guide plate and four longer studs 20 fixed to its outer edge portion to project through the openings 17.

The outer extremities of the studs 20 are reduced in diameter to provide projections 21 which are detachably engaged in openings 22 formed in a spring seat 23. The spring seat 23 has a central pin 24 fixed thereto in axial alignment with the axis of the cylindrical housing and the pin 19, and is directed toward the pin 19.

With the spring seat 23 properly engaged with the studs 20, the adjacent ends of the pins 19 and 24 are spaced apart a distance slightly greater than the thickness of a tripping lever 25, to be 110

later described, and disposed between the ends of the pins.

Engaging the plate like spring seat 23 is a compression spring 26 whose opposite end abuts a plate 27 provided with a central pin 28 which engages a cup-shaped nut member 29 having a threaded connection with the internal threads 7 in the adjacent outer end of the cylindrical housing. The securement of the cup-shaped nut 29 to the housing places the spring in compression to a degree depending upon the distance the cup-shaped nut is threaded into the housing; and as the force of the spring is applied directly to the diaphragm through the four studs 20, the adjustment of the nut 29 controls the pressure at which the mechanism operates. A disc-like diaphragm follower 30 having legs 31 projected from its peripheral edge to engage the bottom of the shallow cup-shaped diaphragm cover, provides a support for the diaphragm when the pressure within the chamber defined by the cover 9, is less than that of the spring.

The normal position of the parts, that is, with no pressure, or a pressure less than that of the spring on the diaphragm exterior, as illustrated in Figure 1, holds the tripping lever 25 in its position closing the switch 14.

The tripping lever 25 is formed from flat bendable metal and is pivotally mounted at its inner end by a cross pin 33 having its outer ends received in suitable openings in the wall of the cylindrical housing at a point above its longitudinal axis. The longitudinal axis of the lever intersects the axis of the cylindrical housing so that the lever passes between the adjacent ends of the pins 19 and 24, as hereinbefore brought out. The free end of the lever extends outwardly of the cylindrical housing through an opening 32 in the lower portion of its wall, and is bent to form an offset substantially U-shaped end portion 34.

The offset at the free end of the tripping lever is such that when the parts are in their positions illustrated in Figure 1, the offset end portion just engages the flange 6 and provides a stop to limit the movement of the lever in one direction.

Mounted from the end portion 34 of the lever is a spring tripping finger 35. This finger 35 is substantially U shaped in cross section and has the inner ends of the side flanges disposed between, and pivotally connected as at 36 with, ears 37 directed outwardly from the offset end of the lever. At the outer end of the tripping finger is a roller 38 and an expansive spring 39 is confined between the finger and the outermost end of the lever offset portion so that the outer free end of the finger is yieldingly urged upwardly toward the cylindrical housing 5, to engage the roller 38 with a V shaped cam portion 40 on a yoke-like contactor carrier 41.

The carrier 41 is preferably formed of two separate members each bent to form one-half of a yoke and having their adjacent ends directed downwardly and riveted together as at 42. The side edges of these ends are cut so as to provide the V shaped cam portion 40 with which the roller 38 engages. The side arms 43 of the yoke extend upwardly to embrace the cylindrical housing 5 and are pivotally connected therewith as at 44. The side arms also extend upwardly beyond their pivotal connection with the cylindrical housing which is on a horizontal axis intersecting the axis of the cylinder, to have their extreme outer ends connected by an insulating panel 45 which is fixed thereto by screws 46 threaded in tapped openings formed in flanges 47 at the

ends of the yoke arms. This insulating panel 45 carries the movable contactors 48 of the switch 14 so that upon movement of the yoke-like carrier 41 the switch is opened and closed.

Movement is imparted to the yoke-like carrier 41 whenever the motion of the tripping lever carries the roller 38 past the apex of the V shaped cam end 40, and as long as the roller 38 is at either side of the apex, the spring 39 holds the carrier 41 at one or the other of its limits of movement. The limits of movement of the carrier 41 are defined by the engagement of the sides of notches 49 in the side arms 43, with stops 50. It is observed that the stops 50 are the ends of pin 33 which mounts the lever 25.

In the position illustrated in Figure 1, the roller 38 engages that side of the V shaped cam end 40 which holds the carrier 41 at its limit of movement maintaining the switch closed, and in the position illustrated in Figure 3, the carrier is held at its opposite limit of movement holding the switch open.

It is obvious that as pressure builds up within the diaphragm cover and the diaphragm moves against the action of the spring 26, the tripping lever 25 will be carried along forcing the roller 38 outwardly toward the apex of the V shaped cam end 40. During this action the compression of the spring 39 increases so that the instant the roller crosses the apex of the V shaped end 40, the stored up energy in the spring 39 snaps the contactor carrier to its opposite position opening the switch. The same snap action, but in the opposite direction, is obtained during the return movement of the tripping lever with lessening of the pressure on the diaphragm.

To preclude the possibility of chattering and poor contact pressure which might result from the roller 38 being held on the exact apex of the cam end 40, play is provided between the lever 25 and its actuating means, which as hereinbefore noted, is afforded by having the distance between the tips of the pins 19 and 24 greater than the thickness of the lever. Hence it is practically impossible for the roller to stand on exact dead center. This condition is even further precluded, when the switch is closed, by providing contact pressure springs 51 for the contactors which are placed in compression by the closing of the switch and tend to move the carrier 41 to its switch opening position.

The switch 14 obviously may be of any suitable design and comprise any number of pairs of contacts to suit various requirements, and in the present instance is a double pole, single throw switch. The movable contactors 48 comprise metal cross pieces 52 to which the contactors per se are secured, and the cross pieces are connected with the panel 45 by stems 53 fixed to the panel and slidably but non-rotatably received in openings 54 in the cross pieces 52. The contact pressure springs 51 are coiled about the stems 53 and yieldably urge the cross pieces outwardly from the panel, movement of the cross pieces by the springs being limited by suitable stop abutments on the ends of the stems.

The stationary contacts 54 are carried by terminal members 55 fixed to a terminal head 56 supported from the cylindrical enclosing housing, preferably by having certain of the bolts 11 passed through it and holding it to the flange 6. The terminal members 55 provide means for the attachment of conductors 57, and it is noted that the terminal members are formed so as to locate the stationary contacts above the cylindrical housing.

between its ends, thus locating the switch within the length of the cylindrical housing.

It is observed that the contactor carrier 41 carries a pin 58 projecting from one of its side arms. 5 This pin provides means for actuating a relief valve 59, which may be used when the switch controls compressors, to relieve the pressure in the outlet line from the compressor after the desired pressure in the tank is reached and the compressor 10 stopped, the purpose being to reduce the load on the compressor motor when it cuts in.

As best shown in Figure 5, the relief valve has an inlet port 60 and an outlet port 61 communicated through a passage 62 which is normally 15 closed between the ports by a ball 63. When the switch is opened the contactor carrier, through the pin 58 engaging a push pin 64, holds the ball from its seat.

The relief valve is conveniently mounted from 20 the cylindrical housing by having an attaching web 65 overlying the flange 6 and having the adjacent screw 11 passed through the web.

The entire mechanism may be suitably enclosed by a casing 66 and is conveniently secured therein 25 by having two of the bolts 11 extended and passed through openings in the back wall 67 of the casing. Nuts secured to these extended bolts draw the entire mechanism against the wall 67 with the diaphragm cover engaging its inner surface 30 and the nipple 13 extending through an opening 68 formed in the rear wall 67. The open front of the casing is closed by a cover 69 shaped to conform to the mechanism and secured to the casing in the conventional manner.

35 From the foregoing description taken in connection with the accompanying drawings, it will be readily apparent to those skilled in the art to which an invention of this character appertains, that this invention provides an exceptionally compact 40 mechanism for translating a relatively slow motion into a snap action, and that this compactness of structure results primarily from the fact that the tubular housing which forms the enclosure for the spring, serves as a support for the entire 45 mechanism. The unitary construction thus afforded greatly facilitates the application of the device to various installations and particularly facilitates its disposition within an enclosing casing.

50 What I claim as my invention is:

1. A switch of the character described comprising a fixed cylinder, a flange on the cylinder, a diaphragm having its peripheral edge portion engaging the flange and movable into the cylinder upon the application of pressure on its exterior, a terminal head having a portion engaging the flange, means for securing the diaphragm to the flange, part of said means securing the terminal head to the flange, a stationary contact carried by the terminal head, a movable contactor engageable with the stationary contact, a contactor carrier pivotally mounted from the cylinder and adapted to carry the contactor from one position to the other, a spring within the cylinder opposing inward movement of the diaphragm, and means responsive to motion of the diaphragm and spring for imparting a snap action to the contactor carrier upon predetermined movement of said means.

70 2. In a pressure switch of the character described having switch instrumentalities operable in accordance with the motion of a diaphragm in response to pressure changes and wherein the switch instrumentalities remain at rest throughout a definite range of pressure change, means to transmit movement of the diaphragm

to the switch instrumentalities comprising, spaced walls, one of which bears directly against one face of the diaphragm, spacing means carried by one wall and bearing against the other wall to maintain said walls in parallel spaced relation at all times, an expansive spring engaging the wall spaced from the diaphragm to oppose movement of the diaphragm in response to increasing pressure, a lever pivoted between the spaced walls and intersecting the axis of said spaced walls and spring, abutments carried by the spaced walls and engageable with opposite sides of said pivoted lever on said intersected axis, the ends of said abutments being spaced apart and the space between said ends being a factor in the determination of the period of rest of the switch instrumentalities, and means to impart movement of the outer free end of the lever to the switch instrumentalities.

3. In a pressure switch of the character described having switch instrumentalities operable in accordance with the motion of a diaphragm in response to pressure changes and wherein the switch instrumentalities remain at rest throughout a definite range of pressure change, means to transmit movement of the diaphragm to the switch instrumentalities comprising, a pair of spaced walls, one of which bears directly against the face of the diaphragm, a plurality of spacing posts carried by one wall and projected toward the other wall to have a readily detachable connection therewith so that said spaced walls are rigidly connected in parallel spaced relation, a compression spring bearing against the wall spaced from the diaphragm to oppose movement

95 of the diaphragm in response to increasing pressure, a lever pivoted between the spaced walls to intersect the axis of the spaced walls and the spring, a lever engaging pin carried by each of

100 said spaced walls, said pins being axially aligned and disposed on said intersected axis of the walls and spring and having their ends spaced apart a predetermined distance, said distance being a factor in the determination of the period of rest

105 of the switch instrumentalities, and means to impart movement of the outer free end of the lever to the switch instrumentalities.

4. In a pressure switch of the character described having switch instrumentalities operable in accordance with the motion of a diaphragm in

110 response to pressure changes and wherein the switch instrumentalities remain at rest throughout a definite range of pressure change, the combination of a supporting cylinder closed at one

115 end by the diaphragm, an adjustable spring stop closing the other end of the cylinder, said spring stop being readily removable to permit access to the interior of the cylinder, a floating carriage within the cylinder and comprising a pair of

120 spaced discs one of which bears against the diaphragm, means carried by one of the discs and readily detachably engaged with the other to maintain the same in a fixed parallel relation, a compression spring confined between said floating carriage and the adjustable spring stop, a

125 lever pivoted within said cylinder between the spaced discs with a portion intersecting the axis of the cylinder and projecting outwardly of the cylinder, opposed abutments axially carried by

130 the spaced discs to engage the lever portion intersecting said cylinder axis and impart movement to said lever, and means associated with the lever portion externally of the cylinder to operate the

135 switch instrumentalities from the movement of the lever, said opposed abutments being spaced

140

145

150

apart a predetermined distance, which distance is a factor in the determination of the duration of said period of rest of the switch instrumentalities and being adjustable by the substitution for 5 the disc engaged by the spring of another disc having a lever engaging abutment with different height.

5. In a pressure switch of the character described having switch instrumentalities operable 10 in accordance with the motion of a diaphragm in response to pressure changes, the combination of a cylinder closed at one end by the diaphragm, a floating carriage in said cylinder comprising a diaphragm engaging disc in flat engagement with 15 the diaphragm, a spring engaging disc and a plurality of spacing posts carried by one of said discs and having a readily detachable connection with the other disc to rigidly hold the discs in parallel spaced relation, a compression spring 20 within the cylinder having one end bearing against said spring engaging disc, a cover having a threaded adjustable connection with the open end of the cylinder whereby removal of the cover enables quick withdrawal of the spring and the 25 spring engaging disc of the floating carriage, a lever pivoted within the cylinder between said discs with its outer free end extending externally of the cylinder, lever engaging pins carried by

the discs with their axes coinciding substantially with the axis of the cylinder and their opposed ends disposed at opposite sides of the lever to be engageable therewith, and means associated with the outer free end of the lever to operate the 80 switch instrumentalities upon movement of the lever in response to motion of the diaphragm.

6. In a pressure switch having switch instrumentalities operable in accordance with the motion of a diaphragm and a spring in response to pressure changes and wherein a pivoted lever imparts said motion of the diaphragm and the spring to the switch instrumentalities and the switch instrumentalities remain at rest throughout a definite range of pressure change, a floating carriage disposed between the diaphragm and the spring and having spaced abutments carried by separable sections of the carriage and disposed at opposite sides of the lever to engage the same and impart movement of the carriage effected by the diaphragm and spring to the lever, said abutments being spaced apart a predetermined distance, said distance being a factor in the determination of the duration of said period of rest of the switch instrumentalities and being readily changeable by the replacement of one of said carriage sections. 85 90 95 100
